RECLINING ARTICLE OF FURNITURE

Anton Lorenz, Buffalo, N. Y.

Application September 17, 1946, Serial No. 697,502

7 Claims. (Cl. 155—105)

1

This is a continuation-in-part of patent application Serial #624,862 relating to "A reclining article of furniture", filed October 26, 1945, and of patent application Serial #642,652 relating to "A reclining article of furniture" filed January 22, 1946.

This invention relates to an article of furniture and more particularly to a reclining article of furniture, wherein the seat and a downward extension of the back-rest form movable links of a polygonal compound linkage swingably mounted on a support, a portion of the latter forming the stationary link of said linkage.

An object of the present invention is to provide a reclining article of furniture of above described type, wherein the movable members of the article of furniture are very well balanced, so that an occupant resting in the article of furniture may bring the movable members of the article of furniture from one position into another position without great effort.

A further object of the present invention is to provide a reclining article of furniture of above described type equipped with a leg-rest swingably mounted on the seat and controlled by a controlling mechanism, wherein the leg-rest may be swung through a relatively large angle during a movement of the movable members of the article of furniture from their sitting position into their extreme reclined position.

Another object of the present invention is to improve on reclining articles of furniture of above described type as now ordinarily made.

With the above and other objects of the invention in view, the invention consists in the novel construction, arrangement and combination of various devices, elements and parts as set forth in the claims hereof, certain embodiments of the same being described in the specification and being illustrated in the accompanying drawings forming part of this specification, wherein:

Fig. 1 is a side elevational view of a reclining wheel-chair in accordance with the invention.

Fig. 2 is a fragmentary side elevational view of the front portion of the wheel-chair shown in Fig. 1, illustrating the holding device for the leg-rest.

Fig. 3 is a sectional view taken along line 3—3 of Fig. 2.

Fig. 4 is a fragmentary side elevational view of a locking device for the movable members of the wheel-chair shown in Fig. 1.

Fig. 5 is a sectional view taken along line 5—5 of Fig. 4.

2

Fig. 6 is a side elevational view of another embodiment of a chair in accordance with the invention, a portion of a side-frame being broken away.

Fig. 7 is a sectional view taken along line 7—7 of Fig. 6, and

Fig. 8 is a side elevational view of still another embodiment of a reclining chair in accordance with the invention, a portion of a side frame being broken away.

Referring now to Fig. 1, 10 generally indicates a support comprising two side frames of tubular design, which are interconnected by a plurality of transverse rods 12 providing a rigid open structure. The support 10 is equipped with wheels 14 of any conventional structure.

A back-rest 16 is pivoted at 18 to lugs 20 of the support 10. Said back-rest 16 has a downward extension 22 projecting downwardly beyond the pivotal connection 18 between the back-rest 16 and the lugs 20 of the support 10. According to the embodiment shown in Fig. 1, said downward extension 22 is integral with the back-rest 16; if desired, however, said extension 22 could be of a separate piece of material rigidly connected with the back-rest 16 in any suitable manner. On each side of the wheel chair, the rear portion of a lower link 24 is pivoted to said extension 22 of the back-rest 16 at 26 below the pivotal connection 18 between the back-rest 16 and the support 10. The front portion of each lower link 24 is pivotally connected at 28 with the lower end portion of a connecting link 30, the upper end portion of which is pivoted to a lug 32 of the support 10 at 34. Thus, the movable extension 22 of the back-rest 16, the movable lower link 24, the movable connecting link 30 and the stationary portion of the support 10 between the pivotal connection 34 of the connecting link 30 with the support 10 and the pivotal connection 18 of the back-rest 16 with said support form the links of a four-bar link mechanism.

The rear portion of a seat 36 is pivoted to the lugs 20 of the support 10 at 38 at a point spaced from the pivotal connection 18 between the back-rest 16 and the lugs 20. On each side of the chair, the upper end portion of a front link 40 is pivoted to the front portion of the seat 36 at 42. The lower end portion of said front link 40 is pivoted to the lower link 24 at 28 in co-axial alignment with the pivotal connection between said lower link 24 and the connecting link 30.

The thus connected four-bar link mechanism 22, 24, 30, 34—18 and the link chain 36, 40 form a polygonal compound linkage. The links of said

polygonal compound linkage may be readily arranged in such a manner and in such proportions that the movable members of the chair are very well balanced, so that an occupant resting in the chair may bring the movable members of the chair from one position (for example, the sitting position shown in full lines) into another position (for example, the extreme reclined position shown in dash and dot lines) without great effort.

A leg-rest 44 swingably mounted on the front portion of the seat 36 at 46 has an upward extension 48. A controlling bar 50 integral with the connecting link 30 swingably mounted on the support 10 at 34 has a controlling surface 52 in the shape of a lug, which is in loose contact with said upward extension 48 of the leg-rest 44. The upward extension 48 of the leg-rest 44 may be held against said controlling lug 52 by means of a spring (not shown). When the controlling lug 52 of the controlling bar 50 is in engagement with said upward extension 48 of the leg-rest 44, the movements of the leg rest are controlled in dependence on the movements of the controlling link 30. Thus, if, for example, the occupant resting in the chair leans the weight of his body against the back-rest 16 so as to swing same about its pivot 18 into the reclined position 16', the seat 36 forming a link of above described polygonal compound linkage and the leg-rest 44 being controlling by the controlling bar 50 integral with the connecting link 30 of above described polygonal compound linkage are brought into the position 36' and 44' respectively.

The movable members of the wheel-chair may be held in any desired position by means of a locking device generally indicated at 54. As best shown in Figs. 1, 4 and 5, said locking device 54 comprises a locking rod 56 swingably mounted on the seat 36 at 58. Said locking rod 56 is slidably engaged with a clamping sleeve 60 having bores 62 for engagement with a bolt 64. Said bolt 64 has a square portion 66 inserted into a corresponding square aperture of a bracket 68 mounted on a side frame of the support 10. A washer 70 is placed on the bolt 64 between the surface of the bracket 68 and the clamping sleeve 60. The head 72 of the bolt 64 rests against a surface of the bracket 68, and a locking knob 74 is screwed on the threaded end of the bolt 64. When the locking knob 74 is loosened, the locking rod 56 may freely slide in the clamping sleeve 60 so that the movable members of the wheel-chair may be freely moved from one position into another one. When the locking knob 74 is tightened, the clamping sleeve 60 is tightly pressed against the locking rod 56, whereby the latter and the seat 36 and those movable members of the chair which are positively connected with the seat are held in their position.

As best shown in Fig. 4, the locking rod 56 has a series of bores 76. A pin 78 passing through a hole of a stop collar 80 adjustably arranged on the locking rod 56 may be selectively engaged with a bore of the series of bores 76, whereby said stop collar 80 is held in a predetermined position on the locking rod 56. When the seat 36 is lifted, the rod 56 slides in the clamping sleeve 60 until the stop collar 80 abuts against said clamping sleeve, whereby the extreme reclined position 36' of the seat and the extreme reclined position of the other movable members of the wheel-chair positively connected with the seat

is limited. As will be readily understood, said extreme reclined position of the various movable members of the wheel chair may be varied and adjusted by a corresponding adjustment of the position of the stop collar 80 on the locking rod 56.

The sitting position of the movable members of the wheel-chair is limited by a stop 82 mounted on the support 10, against which the seat 36 comes to a rest when the latter is in its substantially horizontal sitting position.

As mentioned above, the controlling lug 52 (Fig. 1) is in loose contact with the upward extension 48 of the leg-rest 44, so that the leg-rest 44 with its extension 48 may be disengaged from said controlling lug 52, when the seat 36 is held in a certain position by means of the locking device 54. For example, the upward extension 48 of the leg-rest 44 may be grasped by hand, and the leg-rest may be swung into the position 44a while the seat 36 remains in the sitting position shown in full lines. A holding device generally indicated by 84 and mounted on the seat 36 may be used for holding the leg-rest 44 in a certain position, for example, in said position 44a, relative to the seat 36. As best shown in Figs. 2 and 3, said holding device 84 comprises a rod 86 slidably engaged with a clamping sleeve 88 having bores 90 for receiving a bolt 92 mounted on a lug 93 attached to the seat 36. A square portion 94 of the bolt 92 having a head 95 is engaged with a corresponding square aperture of the lug 93, so that the bolt 92 is prevented from rotation, when a locking knob 96 is screwed on the threaded end of the bolt 92 is turned. Assume that the rod 86 is in the position shown in full lines in Fig. 2, and that the leg-rest has been swung by hand from the position shown in full lines into the position 44a. In order to hold said leg-rest in said position 44a, the locking knob 96 of the holding device 84 is loosened whereupon the rod 86 may be axially displaced in the clamping sleeve 88 until it abuts against said leg-rest in the position 44a as shown in dash and dot lines. Now, the locking knob 96 is tightened, whereby the clamping sleeve 88 is tightly pressed on the rod 86 so as to hold same and the leg-rest in the dash and dot line position. When after a loosening of the locking device 54, the movable members of the chair are brought into a reclined position, the leg-rest will remain in said position 44a relative to the seat 36, until the controlling lug 52 of the controlling bar 50 abuts against the extension 48 of the leg-rest 44. If, after such an abutment the movement of the movable members of the wheel-chair is continued, the position of the leg-rest 44 relative to the seat 36 is altered by the controlling lug 52 in dependence on the movement of the connecting link 30.

According to the embodiment of an adjustable reclining chair shown in Fig. 6, the support 110 comprises the side frames 111 and 113 connected with each other by a plurality of cross bars 112.

The back-rest 116 having a downward extension 122 is pivoted to the support at 118. On each side of the chair the rear portion of the lower link 124 is pivoted to the extension 122 of the back-rest at 126. The lower end portion of a connecting link 130 is pivoted to the lower link 124 at 128. The upper end of said connecting link 130 is pivoted to the support 110 at 134. Again, the movable extension 122 of the back-rest 116, the movable lower link 124, the movable 75 connecting link 130 and the stationary portion

of the support 110 between the pivots 134 and 118 form the links of a four-bar link mechanism.

The lower link 124 has an extension 198 projecting beyond its pivotal connection 128 with the connecting link 130. According to Fig. 6, the lower end portion of the front link 140 is pivoted to said extension 198 of the lower link 124 at 100 at a point spaced from the pivotal connection 128 between the lower link 124 and the connecting link 130. The upper end of the front link 140 is pivoted at 142 to the seat 136, the rear end of which is pivoted to the support 110 at the point 138 spaced from the pivotal connection 118 between the back-rest 116 and the support 110. A leg-rest 144 is swingably mounted on the front portion of the seat 136 at 146. One end of a controlling link 150 is pivoted to said leg-rest 144 at 101, the other end of said controlling link 150 is pivoted at 102 to a controlling arm 103 swingably mounted on the connecting link 130 at 128. As best shown in Figs. 6 and 7, the connecting link 130 is provided with a cam-like lug 104 arranged for engagement with said swingable controlling arm 103, so that the latter may be held in alignment with said connecting link 130 during a swinging movement of the latter about the pivot 134. When the members of the chair are in the position shown in full lines in Fig. 6, the back-rest, seat and leg-rest may be brought into a reclined position, for example, the extreme reclined position 116', 136', 144' shown in dash and dot lines, by swinging the back-rest about its pivot 118.

The movable members of the chair may be held in any desired position by means of a locking device 154 substantially of the type as the locking device 54 shown in Fig. 4. Of course, any other suitable locking device could be used for holding the movable members of the chair in a predetermined position.

As mentioned above, the controlling arm 103 is swingable about the pivot 128. Furthermore, said controlling arm 103 is provided with a lug 105 as shown in Figs. 6 and 7. If the back-rest and seat are held in a predetermined position, for example, the sitting position shown in full lines in Fig. 6, by means of the locking device 154, the leg-rest 144 may be swung by hand about its pivot 146 into the position 144a, wherein the swingable controlling arm, being in the position 103a, is in alignment with the controlling link being in the position 150a. Now, when a slight pressure is exerted on the leg-rest, for example, by the legs of the occupant resting in the chair, the controlling arm 103 and the controlling link 150 are moved slightly beyond said straight line until the lug 105 of the controlling arm 103 abuts against the controlling link, whereby said elements are locked and held in a predetermined position relative to each other, so that the leg-rest is held in the position 144a relative to the seat 136.

The sitting position of the movable members of the chair is limited by a stop 106 mounted on the support for cooperation with the extension 122 of the back-rest 116; the extreme reclined position of the movable members of the chair is limited by a stop 107 arranged on the support 110 for cooperation with the back-rest 116.

According to the embodiment of an adjustable reclining arm chair shown in Fig. 8, the support 210 comprises the side frames 211 and 213 connected with each other by a plurality of cross-bars 206, 207 and 212.

The back-rest 216 having a downward extension 222 is pivoted to the support 210 at 218. On each side of the chair, the rear portion of the lower link 224 is pivoted to said extension 222 of the back-rest 216 at 226. The front portion of said lower link 224 is pivoted at 228 to the lower end of a connecting link 230, the upper end of which is pivoted to the support 210 at 234. Thus, the movable extension 222 of the back-rest 216, the movable lower link 224, the movable connecting link 230 and the stationary portion of the support 210 between the pivots 234 and 218 form the links of a four-bar link mechanism. The rear portion of the seat 236 is pivoted to the support 210 at 238 at a point spaced from the pivotal connection 218 between the back-rest 216 and the support 210. The front portion of the seat 236 is pivoted at 242 to the upper end of a front link 240, the lower end of which is pivoted to an intermediate point of the lower link 224 at the point 208 spaced from the pivotal connection 228 between the lower link 224 and the connecting link 230.

The sitting position of the movable members of the chair shown in full lines is limited by the cross bar 206 acting as a stop for cooperation with the extension 222 of the back-rest 216. The extreme reclined position of the movable members of the chair shown in dash and dot lines is limited by the cross bar 207 acting as a stop for cooperation with the back-rest 216.

The movable members of the chair may be held in any desired position by means of a locking device 254 substantially of the type described above in connection with Fig. 4.

I have described preferred embodiments of my invention, but it is understood that this disclosure is for the purpose of illustration and that various omissions or changes in shape, proportion, and arrangement of parts, as well as the substitution of equivalent elements for those herein shown and described, may be made without departing from the spirit and scope of the invention as set forth in the appended claims.

For example, one or more of the links of the linkage of the chair may be in the shape of a bent link instead of a straight link as shown in the drawings.

Furthermore, one or more of the links of the linkage of the chair may be made of an adjustable link so as to vary the relative positions and movements of the members of the chair.

Furthermore, the invention may be applied to other articles of furniture than the type of chair shown in the drawings, for example, to office chairs, garden chairs, chairs for use in railroad cars, chairs for use in airplanes, lounges, etc.

What I claim is:

1. A reclining article of furniture, comprising a support, a back-rest pivoted to said support, said back-rest having an extension projecting downwardly beyond the pivotal connection between the back-rest and the support, a lower link, the rear portion of said lower link being pivoted to said extension of the back-rest below said pivotal connection between the back-rest and the support, a connecting link, one end portion of said connecting link being pivoted to the front portion of said lower link, the other end portion of said connecting link being pivoted to said support at a point spaced from the pivotal connection between the back-rest and the support, said extension of the back-rest, said lower link, said connecting link and the stationary por-

at a point spaced from the pivotal connection between the back-rest and the support, and a front link, one end portion of said front link being pivoted to the front portion of said seat, and the other end portion of said front link being pivoted to an intermediate point of the lower link between the pivotal connections of the latter with the connecting link and the back-rest.

7. A reclining article of furniture, comprising: 10 a support, a back-rest pivoted to said support, said back-rest having an extension projecting downwardly beyond the pivotal connection between the back-rest and the support, a lower link, the rear portion of said lower link being pivoted to said extension of the back-rest below said pivotal connection between the back-rest and the support, a connecting link, one end portion of said connecting link being pivoted to the front portion of said lower link, the other end portion of said connecting link being pivoted to said support at a point spaced from the pivotal connection between the back-rest and the support, said extension of the back-rest, said lower link, said connecting link and the stationary portion of 25 the support between the pivotal connections of

the connecting link with the support and of the back-rest with the support forming links of a four-bar link-mechanism, a seat, the rear portion of said seat being pivoted to said support at a point spaced from the pivotal connection between the back-rest and the support, a front link, one end portion of said front link being pivoted to the front portion of said seat, the other end portion of said front link being pivoted to the lower link, a leg-rest swingably mounted on the front portion of said seat, and a controlling mechanism in operative relation with a member of the article and said leg-rest for controlling the movements of the latter.

ANTON LORENZ.
